DESIGN FOR A BOWLING ALLEY NEWEL POST

Edward W. Discher, Milwaukee, Wis.

Application June 6, 1940, Serial No. 92,850

Term of patent 7 years

To all whom it may concern:

Be it known that I, Edward W. Discher, a citizen of the United States and resident of Milwaukee, in the county of Milwaukee and State of Wisconsin, have invented a new, original, and ornamental Design for a Bowling Alley Newel Post, of which the following is a specification, reference being had to the accompanying drawing, forming part thereof.

The figure is a perspective view of the bowling alley newel post, showing my new design.

I claim:

The ornamental design for a bowling alley newel post, as shown.

EDWARD W. DISCHER.
